UNITED STATES PATENT OFFICE.

EMIL A. NELSON, OF HALFWAY, MICHIGAN.

CARBURETOR.

Application filed May 1, 1922. Serial No. 557,608.

In the operation of internal combustion engines, it is necessary to "choke" the air supply to the carburetor in starting the engine, that the suction upon the fuel supply nozzle may be increased and initial charges, 5 rich in fuel introduced into the engine cylinder. Further, it is desirable, after the engine starts, that warm air be introduced to aid carburetion, and that as the engine speed increases, additional air be introduced to give a better proportionate mixture of fuel and air for such speeds. Various means have been employed to effect control of air to the carburetor but it has been the common 10 practice to provide a manually operable choke and separate automatically operating means for controlling the admission of air in accordance with engine speeds, but such arrangements are more or less complicated 15 and are inefficient due to changes in weather conditions, giving too lean a mixture for fuel power and speed at times and too heavy a mixture for efficient and economical operation at other times.

20 The object of the present invention is to provide a single manually operable air control whereby the proper amount and kind of air may be admitted under all conditions of operation and a dilution of the ingoing charges effected to give a saving in fuel consumption and efficient operation. A further 25 object is to simplify carburetor construction and to provide a control which may be at all times conveniently adjusted to suit all 30 weather conditions and engine speeds, and give easy starting and maximum efficiency of engine operation with a minimum of fuel consumption.

With the above and other ends in view, 35 the invention consists in providing a carburetor with a single air control member adapted to operate as a choke, and arranged to admit warm air, both warm and atmospheric air in desired proportions, and to 40 open an auxiliary air supply for effecting admixture of air with the carbureted air or combustible charges passing to the engine.

The invention further consists in other 45 matters hereinafter set forth and more particularly pointed out in the appended claims, reference being had to the accompanying drawings in which—

50 Figure 1 is a longitudinal vertical section through a device illustrative of an embodiment of the invention and showing an end portion thereof in side elevation;

Fig. 2 is an end elevation of the same; Fig. 3 is a transverse section substantially upon the line 3—3 of Fig. 1;

55 Figs. 4 and 5 are sections similar to Fig. 3, showing a rotary valve member in different operative positions;

Fig. 6 is a longitudinal sectional detail showing the rotary valve in elevation and moved endwise in its casing to open auxiliary air inlets;

60 Fig. 7 is a sectional detail of a portion of the casing;

Fig. 8 is a detail of the rotary valve detached and partly broken away and in section to disclose its construction; and

70 Fig. 9 is a perspective detail of a Venturi member.

The device may be given any desired general form but as illustrative of a construction suited for use generally in connection with internal combustion engines as embodied in motor vehicle constructions, a substantially horizontal tubular valve casing 1 is provided, said casing being formed adjacent one end with a lateral extension 2 forming the main air inlet 3 for the carburetor and to which a suitable conduit (not shown) may be connected for conducting warm air to the carburetor. The casing 1 is bored inwardly from one end to receive a rotary valve 4 of tubular form having longitudinal slots 5 in its side wall to register with slots or openings 6 in the casing wall 7 which separates the main air inlet 3 from the bore 8 of the casing in which the valve is seated and admit warm air to the casing, said valve being also formed with longitudinal slots 9 in its lower side to register with a pair of longitudinal slots 10 in the lower side of the casing wall and admit atmospheric air to the casing upon proper rotation of the valve. The valve member is also formed with an end wall 11 forming a closure for the open end of the casing bore, said 100 valve projecting from said open end of the casing a short distance and said projecting end being provided with a pair of laterally extending diametrically opposed lugs 12 having screw-threaded openings to receive studs or bolts 13 which are provided with locknuts 14 on their outer ends to lock the studs in the position to which they are adjusted through the openings in the lugs or ears 12, the opposite or inner ends 105 of said studs being adapted to engage cam members 15 secured to or otherwise

110

carried by the end of the casing 1, said cam members having cam surfaces 16 arranged concentric with the axis of the valve and inclined in the direction of rotation of the valve and longitudinally thereof so that a turning movement of the valve will cause the studs to ride up said inclines and move the valve longitudinally in its bore in the casing. To resist this longitudinal movement of the valve and detachably hold the valve in place within the casing, a flat spring 17 is pivotally secured at one end by a bolt 18 to a support 19 on the end of the casing to extend diametrically across the valve end which valve is provided with an axial stud 20 having a reduced outer end to engage in opening 21 in said spring intermediate its ends, the reduced end portion of the stud forming a shoulder to be engaged by the spring and the reduced end serving to detachably hold the spring in place. The valve is rotated by means of a hand operated rod 22 which leads to the dash (not shown) of the car as other support where it may be conveniently manipulated by the driver of the car, and this rod is attached by means of a universal joint 23 to the outer end of a laterally extending arm 24 on the projecting end of the valve.

A tubular extension or continuation 25 of the valve casing 1 provides a mixing chamber and an outlet for the carburetor, the free open end 26 of this tube being adapted to be secured to the uptake pipe of an intake manifold (not shown) of an engine, the bore of this tube being of less diameter than the bore of the valve casing so that an internal annular shoulder 27 is formed at the juncture of the two bores. Fitting within the inner end of the bore of the tube 25 is a restriction member or block 28 which is formed with an axial Venturi opening or passage 29 and through an opening in the lower side of this block projects a vertical nozzle member 30 (see Fig. 1), with said nozzle opening into the most restricted part of the Venturi passage. At its lower end, the nozzle 30 opens into a chamber 31 formed at the lower side of the tube 25 and which chamber is in communication with a float chamber indicated at 32 in Fig. 2, said float chamber containing the usual float (not shown) for controlling the height of fuel therein and in the nozzle, as is the usual practice in carburetor constructions.

At one end, the block 28 is formed with an interrupted flange 33 and a plurality of external longitudinally extending channels or grooves 34 are formed in the block, which grooves cut through the flange 33 and form longitudinal air passages outside the Venturi restriction for by-passing air past the venturi and nozzle for admixture in the mixing chamber 35 with carbureted air entering said chamber from the venturi. The

usual throttle valve 36 is provided in the mixing chamber for controlling the out-flow of the mixture of air and fuel through the outlet 26 to the engine.

The end of the valve 4 adjacent the flanged end of the Venturi block 28, has an end wall 37 formed with a tapered axial opening 38 with the end of the opening of least diameter adjacent and equal in diameter to the diameter of the large end of the Venturi passage 29 in said block, and therefore when the valve is in the position shown in Fig. 1, with said end wall in contact with the end of the block, said passages 34 are closed against the passage of air therethrough, but upon endwise movement of the valve away from the venturi, as shown in Fig. 6, auxiliary air or air for dilution of the combustible mixture in the mixing chamber will be drawn into the casing 1 through the uncovered ends of the slots 6 and 9 in the casing wall and will pass through the several passages 34 into the mixing chamber.

In order to choke the carburetor for the purpose of getting a high suction upon the fuel nozzle so that fuel charges will be drawn into the engine to facilitate starting, the valve 4 is positioned as shown in Figs. 1 and 3, in which position the warm air inlets 6 and cold air inlets 9 are closed, the valve being in its innermost position with its end wall 37 adjacent the Venturi block with the passages 34 closed thereby. Air is therefore prevented from passing through these inlets, and all air except a small amount which enters due to leakage will be cut off from the carburetor and when the engine is turned over in starting, there will be a strong suction upon the fuel nozzle 30 and charges very rich in fuel will be introduced into the engine cylinders to effect easy starting, the valve in this position, functioning as the ordinary choke valve usually employed in carburetor construction and operated by a rod running to the dash of the car.

As soon as the engine starts, the operator will adjust the valve 4 to the position shown in Fig. 4, operating said valve by means of the rod 22 in the same manner in which he would operate the common form of carburetor choke. The slots or inlets 5 in the valve wall are so positioned and proportioned relative to the inlets 6, that this initial movement will open said inlets 6 and permit warm air to enter through the main air inlet 3 and pass through the venturi into the mixing chamber, thus giving a comparatively rich mixture for maintaining engine operation until the engine warms up and becomes normally operative.

As soon as the engine becomes warm, the operator will adjust the valve to the position shown in Fig. 5, in which position the inlets 6 are still open and the inlets 9 are opened to admit atmospheric air to the venturi and

give the proper admixture of air and fuel for normal and low speed running.

For high speeds and after the engine has become thoroughly warmed up, the operator 5 will give the valve 4 a further turn, which turning movement will bring the studs 13 into engagement with the inclines 16 and move the valve endwise, the slots 5 and 8 in the valve wall being so positioned and pro- 10 portioned in width relative to the inlets 5 and 9 in the casing that said inlets will all remain open during this final operation of the valve which effects an endwise movement thereof to open said inlets beyond the end 15 wall 37 of the valve which has been moved away from the end of the venturi to open the several slots 34, and thus air entering the un- covered end portions of the inlets, will be by-passed around the venturi through these 20 slots and admitted to the mixing chamber for the purpose of further diluting the charges.

With this arrangement, the admission of all air to the carburetor is under the direct 25 manual control of the operator who may conveniently and effectively operate the valve to give the proper admixture of fuel and air under all running and other conditions, illuminating uncertainty and placing carburetor operation directly under his immediate 30 and complete control. Further, the present arrangement greatly simplifies and cheapens construction and makes such devices positive 35 and efficient in operation.

It will be understood that the device as 40 shown in the accompanying drawings is merely illustrative of an embodiment of the invention and that such changes as fall within the scope of the appended claims are contemplated.

Having thus fully described my invention, what I claim is:—

1. A device of the character described comprising a casing open at its end and formed with air inlet openings adjacent one end, a rotary valve member fitting within and closing one end of said casing, said valve member being formed with inlet openings to register with the inlets in the casing, 45 a Venturi restriction in the casing, means for supplying fuel to said venturi, said casing being provided with a by-pass for passing air from one end to the other of the venturi, and means for imparting an end- 50 wise movement to said valve member to control said by-pass.

2. A device of the character described comprising a casing forming an air passage therethrough and having a Venturi restric- 55 tion therein with a by-pass for the passage

of air past the venturi, said casing being also formed with a plurality of air inlet openings and an open end, a rotary valve member in the open end of the casing to close the same and to control said inlet openings, means for rotating said valve, a cam for moving said valve longitudinally upon rotation of the valve, said valve being arranged to open said by-pass upon longitudinal movement of the valve, and means for introducing fuel into the Venturi restriction. 65

3. A device as characterized in claim 2 and wherein the casing is provided with cam surfaces arranged to permit limited rotation of the valve and upon further rotation of said valve, to operate to move the valve endwise during such further rotation. 75

4. A device as characterized in claim 2 and wherein the rotary valve member projects from the open end of the casing and is 80 formed with a plurality of longitudinal slots to register successively with the inlet openings in the casing and said casing is provided at its open end with inclined surfaces, means on the valve member to engage 85 said inclined surfaces when said valve is rotated, said inlet openings in the casing, said slots in said valve, and said inclined surfaces being so arranged relatively as to provide a successive opening of the air inlets and a longitudinal movement of said valve with said inlets open. 90

5. In a device of the character described, the combination of a casing forming a main air passage therethrough with a mixing 95 chamber adjacent one end and a series of longitudinal slots forming air inlets adjacent the opposite end, a rotary valve member fitting within the open end of said casing and closing the same and provided with 100 longitudinal slots to register with said slots in the casing upon rotation of the valve, means for rotating said valve, means for moving said valve longitudinally during rotation, a block fitting within the casing with 105 one end adjacent the inner end of the valve, said block being formed with a Venturi passage therethrough opening into the mixing chamber and with longitudinal passages outside the venturi also opening into the mixing 110 chamber and forming a by-pass for air, said valve having an end wall to close the inlet ends of said by-pass passages and to open the same upon endwise movement of the valve, and means for introducing fuel 115 into said Venturi passage.

In testimony whereof I affix my signature.

EMIL A. NELSON.
